(57) **CLAIM**

The ornamental design for a corner protector for instrument sterilization tray, as shown and described.

DESCRIPTION

FIG. 1 is a perspective view of a corner protection for instrument sterilization tray showing our new design;

FIG. 2 is a side view thereof, as taken from the left side of FIG. 1;

FIG. 3 is a side view thereof; as taken from the right side of FIG. 1;

FIG. 4 is a front view thereof;

FIG. 5 is a back view thereof;

FIG. 6 is a top view thereof;

FIG. 7 is a bottom view thereof;

FIG. 8 is a perspective view of a second embodiment of FIG. 1;

FIG. 9 is a side view thereof, as taken from the left side of FIG. 7;

FIG. 10 is a side view thereof; as taken from the right side of FIG. 7;

FIG. 11 is a front view thereof;

FIG. 12 is a back view thereof;

FIG. 13 is a top view thereof; and,

FIG. 14 is a bottom view thereof.

The broken lines of FIGS. 8–14 are included for the purpose of illustrating environmental structure and form no part of the claimed design.

1 Claim, 8 Drawing Sheets
